UNITED STATES PATENT OFFICE.

WILLIAM C. ANDERSON, OF TOLEDO, OHIO, ASSIGNOR TO THE W. L. LIBBEY & SON COMPANY, OF SAME PLACE.

DESIGN FOR THE ORNAMENTATION OF GLASSWARE.

SPECIFICATION forming part of Design No. 19,053, dated April 23, 1889.

Application filed January 21, 1889. Serial No. 297,100. Term of patent 7 years.

To all whom it may concern:

Be it known that I, WILLIAM C. ANDERSON, a citizen of the United States, of Toledo, in the county of Lucas and State of Ohio, have 5 invented a certain new Design for the Ornamentation of Glassware; and I do hereby declare that the following is a full, clear, and exact description of the invention, which will enable others skilled in the art to which it 10 appertains to make and use the same, reference being had to the accompanying drawings, and to the letters of reference marked thereon, which form part of this specification.

The class to which this design relates is 15 that of ornamentation of glassware and the ornamentation of the exterior surface thereof.

The drawings represent, in Figure 1, a bottom plan view of a dish containing the design; and in Fig. 2 a transverse section on lines 20 *x x*, Fig. 1.

The design is applicable to any kind of glassware, such as bowls, plates, jugs, and dishes.

The leading features of my design are a 25 bottom portion consisting of a many-pointed star with triangular checkered portions and isosceles triangles having radiating prisms formed therein, with alternate isosceles triangles having a diamond-shaped base with 30 inscribed five-pointed stars and a checkered triangle above the same.

The flattened portion of the bottom has an 35 ornamentation of a many-pointed star, A, with the triangular-shaped spaces B between the lines, checkered by lines at acute angles, thereby forming diamond-shaped projections. The center C, formed by the crossing of the lines of the star, is of equal height with the 40 spaces B, and is ornamented with inscribed five-pointed stars and intermediate lines crossing a circle formed centrally thereof. The 45 spaces between the outer points of the star are ornamented with a series of prisms, D, radiating toward the center. Upon the circular side, above the bottom portion, is a row of

diamond-shaped projections, E, formed by lines running at acute angles thereon in opposite directions from the flattened portion to the top of the dish. Each diamond-shaped projection E has formed thereon two blended 50 five-pointed stars with a prismatic stud, F, centrally thereof. Above the row of projections E is a series of lines cut in an inverted-V shape, thereby forming a circumferential row of the dish, the intermediate spaces between the points being of V shape and embellished with a series of prisms radiating toward the point of the figure, there being a circumferential row of prismatic studs, H, 55 centrally of the height of the dish. Each 60 triangle G embraces a diamond projection, E, at the base thereof, the triangle above each star being checkered in miniature diamonds. By reason of the ornamentations described, the alternating points of the triangles, the radiating prisms, the checkered triangles, and the prismatic studs, together with the many-pointed star, give to the dish a pleasing symmetry and highly-ornamental appearance. 65

What I claim is—

The design for the ornamentation of glassware herein shown and described, consisting of a many-pointed star having triangular checkered portions within the points and oppositely-arranged isosceles triangles upon the side thereof, each alternate triangle having formed therein radiating prisms and a prismatic stud, the triangles alternate thereto, having a diamond-shaped base with inscribed 70 stars, a checkered triangle above the diamond, and a point extending to the top of the dish, as set forth.

In testimony that I claim the foregoing as my own I hereby affix my signature in presence 75 of two witnesses.

WILLIAM C. ANDERSON.
